UNITED STATES PATENT OFFICE.

CARLETON ELLIS, OF MONTCLAIR, NEW JERSEY, ASSIGNOR TO ELLIS-FOSTER COMPANY, A CORPORATION OF NEW JERSEY.

PROCESS OF MAKING DERIVATIVES OF PETROLEUM-HYDROCARBONS.

1,317,868.

Specification of Letters Patent.

Patented Oct. 7, 1919.

No Drawing. Original application filed August 21, 1913, Serial No. 785,855. Divided and this application filed September 19, 1916. Serial No. 121,910.

To all whom it may concern:

Be it known that I, CARLETON ELLIS, a citizen of the United States, and a resident of Montclair, in the county of Essex and State of New Jersey, have invented certain new and useful Improvements in Processes of Making Derivatives of Petroleum-Hydrocarbons, of which the following is a specification.

10 This invention relates to a process of making derivatives of gasoline and relates in particular to the treatment of gasoline like material obtained through the heat decomposition of kerosene or heavier oil and which 15 contain large amounts of unsaturated materials and in chlorinating such unsaturated products to form dichlor compounds or higher chlorinated bodies as the case may be and furthermore in converting such chlorinated bodies by contact with alkali material into dechlorinated bodies of a useful character.

20 The unsaturated hydrocarbon material is preferably prepared by passing a saturated hydrocarbon such as kerosene through a heated tube, as for example, an iron pipe which is preferably heated to 425 or 480° C. and in some cases may be filled with fragments of contact material such as nickel 25 plated fragments of iron of irregular shape. Also in some cases water may be introduced with the kerosene or other raw oil used and allowed to react with the hydrocarbons during the splitting operation.

30 The product obtained by such heat treatment or other suitable heat treatment of a more or less similar character may then be separated into its lighter and heavier parts by fractional condensation and if desired the 35 fractions obtained in this or other manner are subjected to fractional distillation to obtain particularly certain relatively low boiling fractions of an unsaturated character.

For example kerosene of 42° Bé., was 40 passed through a tube of considerable length heated to such a temperature that the escaping oil vapors were maintained at a temperature of about 465° C., which required a temperature about the tube of approximately 45 630° C. The vapors were passed through an air condenser, then through a water condenser and finally the gases escaping from the latter were pumped through heavy oil in order to remove some of the entrained

condensable material. The gravity of the 55 product as drawn from the heated tube was about 43° Bé., or only 1° lighter than the original kerosene. It consisted of a mixture of products lighter and heavier than kerosene with a certain amount of bodies approximating kerosene in boiling point. This 60 material was distilled and the product collected below 150° C. was redistilled in an ordinary distilling apparatus equipped with a rectifying column and the following fractions were obtained.

Fractions.	Percentage by volume.	Iodin number.	
No. 1, up to 70°	9	310	70
" 2, 70-85°	8.4	233	
" 3, 85-100°	8.6	218	
" 4, 100-115°	9.2	168	
" 5, 115-130°	8	136	
" 6, 130-150°	14	87.8	
" 7, residue above 150°	53	75	

From the foregoing table it will be noted that the iodin number of the lighter fractions is much greater than that observed in the heavier distillates. The products with high iodin numbers chlorinate with great readiness uniting with chlorin in the cold with evolution of heat and forming a more or less non-inflammable liquid. The Chlorinated bodies so obtained may be brought 80 into contact with soda lime or hydrated lime which may be heated to a temperature sufficient to split off their chlorin in large measure forming different varieties of unsaturated bodies or other useful material.

85 The dechlorination may take place with replacement of the chlorin by some other element or radical as for example by an acid radical to form an ester. Thus the chlorinated compounds formed by treatment with 90 chlorin or by union with hydrochloric acid or in any other suitable way may be treated with sodium acetate or other salt of acetic acid to form amyl acetate and other esters according to the nature of the materials 95 used. By employing the salts of other organic acids such as formate, benzoate, etc., similar corresponding esters can be secured. These same esters and other complex esters may be secured from the chlorination products obtained by direct chlorination.

100 The gasoline material obtained by the foregoing heat treatment has in its preferred

form an iodin number not less than 30 but preferably is higher and may be in excess of 100. As stated the products of higher iodin number absorb chlorin with avidity and dichlor compounds are formed when a single double bond is present while in the case of diolefins and the like the chlorination may progress further as desired.

This application is a division of Serial No. 10 785,855, filed Aug. 21, 1913, entitled Motor fuel and process of making same.

What I claim is:—

1. The process of making derivatives of hydrocarbons which comprises passing petroleum oil through a heated zone maintained at a decomposing temperature under such conditions as to form lighter products of unsaturated character, in combining these unsaturated products, after fractional distillation, with chlorin, in reacting on the chlorinated body with an alkali metal salt of an organic acid and in separating the ester formed from other products of reaction.

2. The process of making derivatives of hydrocarbons which comprises passing petroleum oil through a heated zone maintained at a decomposing temperature under such conditions as to form lighter products of unsaturated character, in reacting on these unsaturated products with a chlorinating agent, in reacting on the chlorinated body so formed, with an alkali metal salt of an organic acid and in separating the ester formed from other products of reaction.

3. The process of making derivatives of hydrocarbons which comprises passing petroleum oil through a heated tube maintained at a decomposing temperature under such conditions as to form very light products of unsaturated character, in combining these unsaturated products with chlorin, in reacting on the chlorinated body with a salt of an organic acid and in separating the ester formed from other products of reaction.

4. The process of making derivatives of hydrocarbons which comprises passing petroleum oil through a heated zone maintained at a decomposing temperature under such conditions as to form lighter products of unsaturated character, in combining these unsaturated products with chlorin, in reacting on the chlorinated body with a salt of acetic acid and in separating the ester formed from other products of reaction.

5. The process of making derivatives of hydrocarbons which comprises bringing petroleum oil into a heated zone maintained at a decomposing temperature under such conditions as to form lighter products of unsaturated character, in combining the resulting olefin products with chlorin and in reacting on the chlorinated body with an acetate.

6. The process of making derivatives of hydrocarbons which comprises passing petroleum oil with water through a heated zone maintained at a decomposing temperature under such conditions as to form lighter products of unsaturated character, in combining the resulting olefin products with chlorin and in reacting on the chlorinated body with an alkali metal salt of an organic acid. 75

7. The process of making derivatives of hydrocarbons which comprises passing petroleum oil with water through a heated tube maintained at a decomposing temperature under such conditions as to form lighter products of unsaturated character, in combining the resulting olefin products with chlorin and in reacting with the chlorinated body with an alkali metal salt of an organic acid. 80

8. The process of making derivatives of hydrocarbons which comprises passing petroleum oil with water through a heated zone maintained at a decomposing temperature under such conditions as to form lighter products of unsaturated character, in combining the resulting olefin products with chlorin, and in reacting with the chlorinated body with a salt of an organic acid. 85

9. The process of making derivatives of hydrocarbons which comprises passing petroleum oil through a heated zone maintained at a decomposing temperature under such conditions as to form light products of unsaturated character, in combining these unsaturated products with chlorin and in reacting on the chlorinated body with an alkali metal salt of acetic acid. 95

10. The process of making derivatives of hydrocarbons which comprises cracking kerosene under such conditions as to form olefin material, in saturating said olefin material with chlorin to form chlorin compounds and in contacting said chlorin compounds with a reagent capable of replacing chlorin. 105

11. The process of making derivatives of hydrocarbons which comprises passing a petroleum oil into a heated zone maintained at a decomposing temperature under such conditions as to form lighter products of an unsaturated character, in chlorinating these unsaturated products and in subsequently replacing the chlorin by another element or radical. 115

12. The process of making derivatives of hydrocarbons which comprises cracking kerosene under such conditions as to form olefin material having an iodin number exceeding 30°, in chlorinating said olefin material to form chlorin compounds and in contacting said chlorin compounds with a reagent capable of replacing chlorin. 125

13. The process of making derivatives of hydrocarbons which comprises cracking a 130

petroleum oil under such conditions as to form lighter products of an unsaturated character, in chlorinating these unsaturated products and in subsequently replacing the 5 chlorin by a substituent.

14. The process of making derivatives of hydrocarbons which comprises cracking kerosene under such conditions as to form olefin material, in chlorinating said olefin material to form dichlor compounds and 10 in contacting said dichlor compounds with a reagent capable of replacing chlorin.

15. The process of making derivatives of hydrocarbons which comprises cracking a 15 petroleum oil in a heated zone under such conditions as to form lighter products of an unsaturated character, in chlorinating these unsaturated products with free chlorin and in subsequently replacing the chlorin.

20 16. The process of making derivatives of hydrocarbons which comprises passing petroleum oil through a heated zone at a temperature between 425° and 480° C. under such conditions as to form olefin material 25 and in chlorinating said olefin material.

17. The process of making derivatives of hydrocarbons which comprises cracking petroleum to form olefin material, in treating said olefin material under such conditions as to form chlorin compounds and 30 in contacting said chlorin compounds with a reagent capable of replacing chlorin.

18. The process of making derivatives of hydrocarbons which comprises passing a 35 petroleum oil into a heated zone maintained at a decomposing temperature under such conditions as to form lighter products of an unsaturated character having an iodin number above 30; in chlorinating these unsaturated products and in subsequently replacing the chlorin.

19. The process of making derivatives of hydrocarbons which comprises cracking an

oil under such conditions as to produce light volatile hydrocarbons of an unsaturated character having an iodin number in 45 excess of 30, in exposing said products to the action of chlorin in the cold whereby chlorin is absorbed with the evolution of heat forming a more or less non-inflammable liquid and in bringing said liquid into contact with 50 a reagent capable of replacing chlorin.

20. In the preparation of derivatives of hydrocarbons from unsaturated hydrocarbons the step which comprises treating cracked petroleum having an iodin number 55 of more than 30 with chlorin and in subsequently contacting the product with a reagent capable of replacing chlorin.

21. In the preparation of derivatives of hydrocarbons from unsaturated hydrocarbons the step which comprises treating cracked petroleum having an iodin number 60 of more than 30 with chlorin and in subsequently heating the product with a reagent capable of replacing chlorin.

22. The process of making derivatives of hydrocarbons which comprises cracking an oil under such conditions as to produce light volatile hydrocarbons of an unsaturated character having a high iodin number, in 70 exposing said products to the action of chlorin in the cold whereby chlorin is absorbed with the evolution of heat forming a relatively non-inflammable liquid and in contacting said liquid with a reagent capable of 75 replacing chlorin.

23. In the preparation of hydrocarbons from unsaturated gasoline material the step which comprises treating gasoline material having an iodin number of more than 100 80 with chlorin and in subsequently contacting the product with a reagent capable of replacing chlorin.

CARLETON ELLIS.
